Primary Examiner — Kevin K. Rudzinski*Assistant Examiner* — Jessica A. Junkins(74) *Attorney, Agent, or Firm* — Michael A. Catania(57) **CLAIM**

The ornamental design for a duffel as shown and described.

DESCRIPTION

FIG. 1 is a front perspective view of the duffel claimed herein;

FIG. 2 is a front elevation view thereof;

FIG. 3 is a rear elevation view thereof;

FIG. 4 is a side elevation view thereof;

FIG. 5 is a side elevation view thereof;

FIG. 6 is a top plan view thereof; and,

FIG. 7 is a bottom plan view thereof.

The wide dash broken lines are to illustrate portions of the duffel and form no part of the claimed design. The short dash broken lines are to illustrate stitching and form no part of the claimed design.

1 Claim, 6 Drawing Sheets(56)
